UNITED STATES PATENT OFFICE.

MARIE FRANÇOIS JOSEPH LEONCE JUMEAU, OF Pnom-PENH, CAMBODIA, FRENCH
INDO-CHINA.

FLYING-MACHINE.

1,135,191.

Specification of Letters Patent. Patented Apr. 13, 1915.

Application filed January 16, 1912. Serial No. 671,496.

To all whom it may concern:

Be it known that I, MARIE FRANÇOIS JOSEPH LEONCE JUMEAU, civil engineer, citizen of France, residing at Pnom-Penh, in the Kingdom of Cambodia, French Indo-China, have invented new and useful Improvements in Flying-Machines, of which the following is a specification.

This invention relates to a flying machine in which the sustentating force is created by the reaction of the atmosphere on aerial turbines or blade wheels which rotate freely upon supporting shafts carried by the machine frame.

The air current produced relatively to the machine by the progression thereof under the action of the propeller has thus for its effect to rotate the blade wheels and to cause the machine to rise. Should the propulsive power fail, for any reason, the flying machine will fall by gravity and the air current generated by the fall with regard to the machine will react on the blade wheels and the wheels being capable of rotating freely upon their shafts, an efficient braking action will result so that the machine instead of falling suddenly will have a smooth descent similar to that of an apparatus provided with a parachute.

Another advantage of a flying machine provided with the aerial blade wheels above mentioned is that the centers of pressure on said machine are stationary whatever the direction of the driving wind may be, said centers of pressure being always located at the centers of the blade wheels. It results therefrom that by arranging the center of gravity on a vertical line with the center of pressure, the stability of the machine in flying is considerably greater than that of the known machines in which the position of the center of pressure varies according to the direction of the relative wind.

In the annexed drawings: Figure 1 is a front view of a flying machine constructed in accordance with the invention, Fig. 2 is a plan view, Fig. 3 is a side view, Figs. 4, 5 and 6 are diagrammatical views showing the manner of constructing the aerial blade wheels.

The characteristic feature of the flying machine consists in the arrangement on the machine of turbines or aerial blade wheels A which in the construction shown are two in number and rotate freely upon shafts B

carried by arms C, secured to the frame D of the machine. The shafts B are in a position slightly inclined to the normal to the direction of flight. The blades of the wheels are so arranged that the wheels rotate in opposite directions for compensating the torque resulting from the rotation. The front part of the frame D carries the propulsive device comprising the motor E and the screw propeller F. At the rear end the frame D carries the vertical rudder G and the horizontal rudder H formed of two planes rigidly secured together. The planes I are stationary and act as a centerboard.

The aviator seated at J operates the vertical rudder G by his feet, through the medium of the lever K. The lever L serves to control the horizontal rudder. The controlling wheel M is arranged to move, by means of the wheel N, the counterweights O, formed by heavy bodies capable of sliding in opposite directions along the cross rods P for the purpose of maintaining the lateral stability and permitting in the curves the necessary inclination of the machine.

The aerial turbines or blade wheels are constructed as follows: a b (Fig. 4) are two concentric cylindrical surfaces having the radii c and d and limited by parallel planes i i and j j respectively, symmetrical with regard to the plane f f. Two lines e l and e m are drawn through the axis e of the cylinders, and cut the circles j at l and m and the circles i at n and o. The straight lines l m and n o will be taken as the generatrices of a winding surface which forms one blade V of the wheel. The different blades of the wheel are determined by drawing an appropriate number of radial equidistant lines similar to e l and e m through the axis e as shown in Fig. 5 and connecting the intersection points in the manner described for the points l m n o.

In practice, the circles j are embodied in the form of a circular rim Q having a channel cross section as shown in Fig. 6 and provided in its flanges with a number of holes twice that of the blades or vanes. The circles i are formed by disks R which are secured to a hub S or made in one piece with the same. The disks R are provided with the same number of holes, and spokes T of steel wire are arranged to connect appropriate holes of both series in a manner similar to the lines l n and m o of Fig. 4. Each of

the warped surfaces above mentioned which forms a blade V is made of a piece of canvas rigidly secured to the corresponding spokes. The canvas blade is wound at its edges over 5 the spokes; it is first glued thereon which permits of obtaining a regular smooth surface and then sewn for avoiding any displacement or deformation of the blade. The hub is preferably provided with ball 10 bearings.

The aerial blade wheels above described are exceedingly light while being of a strong construction and they are applicable with 15 advantage in all apparatus utilizing wind as a source of motive power.

Having now described my invention what I claim as new and desire to secure by Letters Patent is:

1. In a flying machine, in combination, a 20 frame, a vertically rotating screw propeller at the forward end of said frame, means for actuating said screw propeller, shafts symmetrically arranged on both sides of the frame at the rear of the screw propeller, 25 said shafts being slightly inclined to the rear, hubs loosely mounted on said shafts so as to rotate freely thereon, rims encircling the hubs, wires stretched in radial planes between the hubs and the rims so that pairs of 30 said wires define warped surfaces, and fabric vanes stretched over said pairs of wires,

said vanes having relatively long narrow channels therebetween, substantially as described and for the purpose set forth.

2. In a flying machine, in combination, a 35 frame, a vertically rotating screw propeller at the forward end of said frame, means for actuating said screw propeller, shafts symmetrically arranged on both sides of the frame at the rear of the screw propeller, 40 said shafts being located in vertical planes parallel to the longitudinal axis of the machine and slightly inclined at the top to the rear, hubs loosely mounted on said shafts so as to rotate freely thereon, rims having a 45 width shorter than the length of the hubs and encircling the same; wires stretched in radial planes between the hubs and the rims so that pairs of said wires define warped surfaces, and fabric vanes stretched over 50 said pairs of wires, said vanes having relatively long narrow channels therebetween, substantially as described and for the purpose set forth.

In testimony whereof I have signed my 55 name to this specification in the presence of two subscribing witnesses.

MARIE FRANÇOIS JOSEPH LEONCE JUMEAU.
